UNITED STATES PATENT OFFICE

LEON E. LA BOMBARD, OF WEST NEWTON, AND MELVIN H. SIDEBOOTHAM, OF NEWTONVILLE, MASSACHUSETTS, ASSIGNORS TO SPECIALTY AUTOMATIC MACHINE COMPANY, OF CHELSEA, MASSACHUSETTS

ARTICLE HOLDER

Application filed January 28, 1927. Serial No. 164,210.

This invention relates to holders or containers for shirts or similar articles or goods when kept in stock or exposed for sale, or to contain such articles returned from a laundry, especially the latter purpose.

The invention has particular reference to means for not only protecting the articles from dust and dirt, but also to retain such articles as soft shirts, or dress shirts, which are liable to shift or slide in a container, in flat or un-crumpled condition.

A particular object of the invention is to provide a garment holder having a stiffener, which stiffener is so constructed or shaped that, although normally flat, will be converted by the act of inserting a garment in the container or holder, to a form which will greatly increase its longitudinal stiffness.

Another object is to provide means for cooperating with the container or holder to facilitate insertion of a garment in smooth folded condition in the holder, the said inserting means being removable when desired.

With the above-mentioned objects in view, the invention consists in the holder or container, and an inserter, substantially as hereinafter described and claimed.

Of the accompanying drawings:

Figure 1 is a face view of the package, with the inserter as well as a folded shirt in the holder.

Figure 2 is an end view looking upward from the lower end of Figure 1.

Figure 3 represents a section on line 3—3 of Figure 1.

Figure 4 represents a section on line 4—4 of Figure 1, but omitting any enclosed garment, the members being illustrated as well separated, in the interest of clearness.

Figure 5 is a rear view.

Figure 6 is a face view of the holder alone, empty and in the normal flat condition as when not in use.

Figure 7 is a face view of the inserter alone.

Figures 8 and 9 are, respectively, side and end views of the inserter alone.

Figure 10 is a face view of another form of holder.

Figure 11 represents a section on line 11—11 of Figure 10.

Figure 12 is a partial face view of another form of holder.

Figure 13 represents a section on line 13—13 of Figure 12.

Figure 14 is a partial face view of another form of holder.

Figure 15 represents a section on line 15—15 of Figure 14.

Similar reference characters indicate similar parts in all of the views.

The holder, which may contain a folded garment either alone or permanently or temporarily with the member which is first used as an inserter, comprises a card board back member 12 and a flexible front member 13 preferably consisting of tissue paper of less length than the back member, the side margins of the front member being folded over the side edges of the back member and adhesively secured. The back member is creased parallel with its side edges as indicated at 14, for a purpose presently explained.

The front and back members of the holder are of such relative areas laterally that when in stock or not in use both members lie flat together (Fig. 6), but when a shirt such as indicated at α in Figures 1, 2 and 3 is inserted between the two members, the tissue member 13 exerts a pull on the extreme edges of the back member and swings or bends the marginal portions of the latter, mostly on the crease lines 14, up from a flat plane. This slightly reduces the width of the holder and expands it as to thickness; but the important result is that the conversion of the back to a form or shape having transversely angular or curved marginal portions renders the holder as a whole so stiff longitudinally that the package can be handled quite freely without disturbing its substantially flat shape and the consequent proper folded condition of the enclosed protected garment.

To reduce liability of tearing the thin front member 13 when inserting a garment,

and to aid in transmitting the above-mentioned pull on the side edges of the back member 12, the edge of the thin member at what may be described as the mouth or entry end of the holder, is reinforced by double-folding said edge of the thin member so as to provide three or four thicknesses of the paper as indicated at 15 in Figures 1, 4 and 5. Enclosed within said folds is a cord or string 16 the ends of which, as well as the ends of the folds 15, pass over the extreme edges of the member 12 and are adhesively secured to the back thereof. To still further reinforce the corners where the pull is exerted when a garment is inserted in the holder, patches or tabs 17 are illustrated in Figures 1 and 5, said patches being of suitable material such as strong kraft paper adhesively secured to the front and back of said corners and extending around or over the edges of the front and back members. While the reinforcements just described provide a strong and durable structure, we do not limit ourselves thereto. Either of said reinforcements may be omitted if the garments to be placed in the holders are of a light and not bulky character so as not to require such multiple reinforcements.

To facilitate the placing of a folded garment in the holder, we employ an inserter which can either be removed after performing its function or can be left in the holder with the garment, said inserter being of a character which, when left in the holder, protects the entire shirt front as hereinafter explained. Said inserter comprises a strip of suitable material such as card board, said strip being cut and creased to form two long sections 18, 19, with an intermediate connecting narrow section 20, the latter being cut out at its middle to provide an opening 21 and a lip 22 (Figs. 1, 2, 7 and 9). The strip is foldable on the crease lines which define the sections from each other, and the sections 18, 19, at their separate or free ends, are tapered as at 23 and the end edges are recessed as at 24. The section 18 is longitudinally creased at 25, near its side edges, and adjacent to the section 20 is provided with relatively small ears 26 (Figs. 1, 2, 7, 8 and 9).

The strip 18, 19, 20, when folded on the transverse crease lines, preferably substantially equals, in length, the back member 12 of the holder, but is slightly narrower. It is employed, primarily, for the purpose of effecting a smooth insertion of a folded garment such as a shirt in the holder as hereinafter described; when left in the holder, with the shirt, it protects the collar band and the bosom of the shirt including that portion of the latter which would otherwise be exposed above the reinforced edge of the holder member 13.

In use, a garment such as a shirt is folded about the back member 19 of the inserter, a portion of the shirt being folded over the recessed and tapered end of said member 19 and turned upward against the back of said member, the correct folding being facilitated by utilizing the hole 21 in the section 20 as a visual guide for the proper location of the center of the neck band of the shirt, the usual button hole a' in said neck band indicating said center. In other words, the hole 21 in the inserter section 20 indicates the proper centering of the shirt laterally. After said folding, the front member 18 of the inserter is laid down over the entire front of the shirt and then, in its doubled condition, with the shirt, is inserted into the holder, this being illustrated by Figures 1, 2 and 3. The tapered ends 23 of the inserter sections 18, 19, facilitate easy entrance. Owing to the fact that the section 18 covers the shirt bosom and the usual front buttons thereof, such buttons, or any frills of the shirt bosom, can not catch on the edge of the member 13 of the holder and either tear said member or interfere with smooth insertion to place.

After the shirt is smoothly positioned, the inserter can be readily withdrawn so as to leave the front of the shirt perceptible through the member 13 which is usually more or less transparent. Such removal is easily effected by grasping the lip 22 with one hand and with the other hand grasping the portion of the shirt which overlies the recesses 24 of the members 18, 19, and then pulling in opposite directions. If desired however, especially when the garment is a dress shirt or if visibility of its material and pattern is not desired because it is to be put away in stock, the inserter can be advantageously left in the holder, with the shirt, to be removed at any later time. When so left, the portion of the shirt which would otherwise be exposed above the edge 15 of the holder member 13 is covered and protected as well as the rest of the shirt bosom. And the ears 26 of the inserter section 19 afford protection to such portions of the shirt as tend to bulge outward above the reinforced corners of the holder front member 13.

In Figures 10 to 15 inclusive we illustrate structures which not only provide for reinforcing the upper unattached edges of the thin members 13 but also maintain the extreme edges at sufficient distances from the back members so that garments can be readily inserted into the pockets or spaces between the front and back members without catching on said extreme edges.

Although in said Figures 10 to 15 no attempt has been made to include illustration of an inserter, it is to be understood that inserters such as illustrated by Figures 7, 130

8 and 9 are employed in the holders illustrated by Figures 10 to 15 in the same manner that such combination is illustrated by Figures 1 to 4.

5 In the structures illustrated by Figures 10 and 11 a strip of strong flexible material 30, such as kraft paper, is adhesively secured to the outer surface of the upper margin of the thin front member 13, preferably 10 extending around the side edges and onto the back of the stiff member 12, and said strip is longitudinally creased as at 31 to cause the extreme edge of both the strip and the member 13 to stand away from the back member so that a garment can be readily 15 moved past said extreme edge without catching thereon. Said extreme edge is illustrated as scalloped, such formation not only imparting an ornamental appearance to said edge but also providing a series of protuberances which, if a garment should catch thereon, will only bend in with the garment and permit it to smoothly pass.

In the structure illustrated by Figures 12 25 and 13, a strip 32, similar to the described strip 30, is adhesively secured to the inner surface of the margin of the front member 13, instead of to the outer surface as in Figures 10 and 11. Such strip, so located, 30 does not need to be creased because the well-known characteristic of adhesive on a strip causes the strip to curve when dry and therefore the margin of the front member, and its attached strip 32, automatically assumes such a transversely curved form as 35 illustrated by Figure 13.

Figures 14 and 15 illustrate a structure in which a strip of kraft paper or similar material is doubled over the edge of the member 13 and adhesively secured so that said strip presents a rounded surface past which a garment can be readily moved without catching, a portion of said surface curving away from the back member 12.

45 Figures 11, 13 and 15, which are sectional views on lines 11-11, 13-13 and 15-15 of Figures 10, 12 and 14 respectively, illustrate the reinforcing strips as thicker than those used in practice, this being done in the 50 interest of clearness of illustration.

Having now described our invention, we claim:

1. The combination with an article holder comprising front and back members connected at opposite edges, of an article inserter comprising two sections connected solely at one end and having oppositely tapered margins at its other end, and an article completely enclosed between said inserter sections.

2. The combination with an article holder comprising front and back members connected at opposite edges, of an article inserter comprising two sections with an inter-

mediate section having an opening at its middle.

3. The combination with an article holder comprising front and back members connected at opposite edges, of an article inserter comprising two sections connected at one end and having a projecting lip at said connected end, the edges of the other ends of said sections being recessed. 70

4. The combination with an article holder comprising front and back members connected at opposite edges, of an article inserter comprising two sections connected at one end, one of said sections being creased along lines parallel with its side edges. 75

5. The combination with an article holder comprising front and back members connected at opposite edges, of an article inserter comprising two sections connected at one end, one of said sections having laterally projecting ears adjacent to the connections between the two sections, and an article completely enclosed between said sections of the inserter. 80

6. An article holder comprising a thin flexible front member and a relatively stiff back member, the two members being connected at opposite edges, the thin front member having an unattached edge provided with means for causing the extreme edge to stand away from the stiff back member to facilitate entrance of a garment to the space between the two members. 90

7. An article holder comprising a thin flexible front member and a relatively stiff back member, the two members being connected at opposite edges, the thin front member having an unattached edge provided with a supplemental reinforcing strip having a normal shape to maintain the extreme edge deflected away from the stiff back member. 100

8. An article holder comprising a thin flexible front member and a relatively stiff back member connected together at opposite edges, the thin front member having an unattached edge provided with a strip of tough flexible material adhesively secured to it, said strip being treated to cause it to maintain a transversely curved condition. 110

In testimony whereof we have affixed our signatures.
